**COMBINED STABILIZER AND END CAP FOR AN
ELECTRIC PRESSING IRON HANDLE**

Bernard B. Bluestein, Des Plaines, and Norman A. Stein-kamp, Chicago Heights, Ill., assignors to Sunbeam Cor-poration, Chicago, Ill.

Filed July 17, 1972, Ser. No. 272,550

Term of patent 14 years

Int. Cl. D7—05

U.S. Cl. D7—204

FIG. 1 is a perspective view of a combined stabilizer and end cap for an electric pressing iron handle embodying our new design;

FIG. 2 is a top plan view thereof;

FIG. 3 is a rear elevational view thereof;

FIG. 4 is a side elevational view thereof; and

FIG. 5 is a front elevational view.

The broken lines in FIG. 1 are shown for purposes of describing the environment only.

We claim:

The ornamental design for a combined stabilizer and end cap for an electric pressing iron handle, as shown and described.
